PROCESS FOR THE SOLVENT EXTRACTION
OF PETROLEUM OILSDavid R. Merrill, Long Beach, Calif., assignor to
Union Oil Company of California, Los Angeles,
Calif., a corporation of California

Application November 27, 1933, Serial No. 699,904

6 Claims. (Cl. 196—13)

This invention relates to the treatment of oils, such as mineral lubricating oils, by extraction with selective solvents.

It has been found that desirable paraffinic hydrocarbons can be separated from the undesirable olefinic, naphthenic and/or aromatic compounds by the use of solvents which selectively dissolve the undesirable hydrocarbons but which exhibit only a very limited solvent power upon 10 the desirable paraffinic hydrocarbons.

When I use the term "paraffinic hydrocarbons" I mean those highly saturated compounds which are present in petroleum characterized by a low temperature viscosity susceptibility, i. e., they 15 exhibit a minimum change in viscosity for a given change in temperature, and characterized by relative stability to air or sunlight, exhibiting little tendency toward discoloration or sludge formation. This definition is not meant to include those compounds which are usually solid or semi-solid at ordinary temperatures and which are known as "wax" or "petrolatum". As a matter of convenience hereafter, I will refer to the undesirable components, such as olefinic, naphthenic and/or aromatic hydrocarbons as the 20 "non-paraffinic" components of petroleum. These fractions are characterized by a relatively high temperature viscosity susceptibility and are relatively unstable to air or sunlight, exhibiting discoloration and sludge formation.

A further indication of the purity of a lubricating oil is its viscosity gravity constant. This constant is an index of the paraffinicity or naphthenicity of an oil. A high value represents 35 a high degree of naphthenicity while low values indicate relatively greater paraffinicity. Lubricating oils from natural crudes range from about 0.903 viscosity gravity constant for an extreme Gulf Coast type to 0.807 for an extreme Pennsylvania type, or even beyond. The viscosity gravity constant referred to in this application has been determined by the method employed by Hill and Coates as set forth in the Journal of Industrial and Engineering Chemistry, vol. 20, page 40 641, of 1928.

A number of selective solvents for extraction have been found; for example, it has been shown that such materials as liquid sulphur dioxide, beta beta dichlorethyl ether, chloranilene, nitro-benzene, aniline and furfural are highly selective as 45 solvents for the non-paraffinic hydrocarbons. These solvents may be used alone or modified by the presence of such agents as carbon bisulphide, xylene, benzene, toluene, carbon tetrachloride, ethers, tetrachlor-ethane or the like.

When these relatively heavy solvents are commingled with petroleum or petroleum fractions under the proper conditions of temperature, the undesirable non-paraffinic hydrocarbons pass into solution to a greater or less extent but the desirable paraffinic hydrocarbons remain largely undissolved. The solution of undesirable hydrocarbons and solvent settles to the bottom of the container and forms what is known as an extract phase. The relatively light paraffinic hydrocarbons rise to the top of the vessel and form a raffinate phase. These phases are then readily separable by ordinary decantation means. The raffinate phase is usually found to contain a small quantity of the selective solvent and the extract phase ordinarily contains a relatively large quantity of the solvent. These fractions may be purified by distillation whereby the solvent is distilled away from the hydrocarbon oils.

In selectively extracting certain oils containing substantial proportions of highly aromatic or non-paraffinic fractions characterized by high viscosity gravity constant, for instance, a residual oil such as a Kettleman Hills long residuum which was deasphaltized and dewaxed by liquid propane, difficulty has been encountered in obtaining the desired separation of the raffinate and extract phases, especially with selective solvents, such as dichlorethyl ether or sulphur dioxide which are not good solvents for asphalt. Under 20 the conditions necessary to produce a high grade raffinate characterized by low viscosity gravity constant, the raffinates in the various states tend to form with the extract phases a finely divided dispersion which does not break readily. The 25 raffinate phase is slow to coalesce and consequently the extract phase entrains part of the raffinate as it is removed from the system. Although I do not desire to be limited by this theory, I believe that the asphaltic components 30 and perhaps other similar materials present in the oil are colloidally active in emulsifying the extract and raffinate phases whereby phase separation is hindered. Phase separation of such oil is 35 especially difficult when the selective solvent employed has low solvent power for asphalt.

It is also difficult to obtain the desired separation of oil in a rejection stage in which an extract phase from an extraction stage is cooled to produce a rejected raffinate. In many cases, particularly at low temperature, the rate of separation of this rejected oil is very slow, due apparently to either a supersaturation of the raffinate components in the extract phase and/or to a separation of these components in extremely fine 45 50 55

dispersed form characterized by a slow rate of coalescence of the droplets. In consequence, the formation of large droplets which would rise to form a continuous upper raffinate phase is hindered.

It is an object of my invention to facilitate the separation of the raffinate and extract phases during solvent extraction whereby loss of raffinate entrained in the extract phase is substantially reduced.

It is a further object of my invention to accelerate phase separation during the solvent extraction of oil containing substances which tend to stabilize the dispersion of the extract and raffinate phases.

It is another object of my invention to facilitate the separation of a rejected insoluble oil from an extract phase produced by a prior extraction.

I have found that these difficulties can be overcome by increasing the proportion of raffinate to extract phase prior to extraction and/or rejection of oil in the presence of a selective solvent. The increased proportion of raffinate results in the production of a dispersion of raffinate and extract phase during solvent extraction characterized by a large number of droplets of larger size than those produced when only a relatively small proportion of raffinate is present. The proportion of raffinate to extract phase can be increased in several ways. For instance, to an oil characterized by a relatively small proportion of valuable paraffinic components which are separable from extract phase with difficulty during extraction with a selective solvent, a relatively highly paraffinic oil may be admixed prior to solvent extraction for the purpose of increasing the ratio of raffinate to the extract phase. This highly paraffinic oil may come from any suitable source. It may be an unextracted oil containing a larger proportion of paraffinic components to non-paraffinic components than the oil which is difficultly separable during solvent extraction.

A suitable source of highly paraffinic oil for intermixture with the less paraffinic oil is a raffinate produced by extraction of mineral oil with a selective solvent. This raffinate may be derived from the same or a different source than the oil to be extracted according to the present invention.

As illustrative of my invention, the oil characterized by the above mentioned difficulties during extraction may be mixed with a portion of the raffinate phase produced in the same extraction. Also the extract phase characterized by difficulty of separation of oil rejected by cooling the same may be mixed with a portion of the oil rejected therefrom.

By intermingling a portion of the raffinate phase with incoming feed, preferably at a temperature above that of the settling chamber in which phase separation of extract and said raffinate occurs, the droplets which form in the mixture are of larger size and the coalescence of the raffinate is accelerated. Also, the concentration of oil in solution in the extract phase will be increased with the result that on subsequent cooling to the temperature of separation, the quantity of oil separated will be larger and there will be less tendency for a state of supersaturation to exist and a greater tendency for the products to coalesce.

The drawing is a diagrammatic view of a preferred form of apparatus suitable for carrying out my invention.

Referring to the figure, oil to be extracted is introduced into the system through line 10 controlled by valve 11 by action of pump 12. In mixing chamber 15, with which line 10 connects, the oil is intermixed with solvent introduced via lines 16 and 17, valve 18 and pump 19 and with raffinate introduced via lines 37 and 17 recycled from settler 30 to be described. Rejected oil, described below, from rejection settler 45 may also comprise part of the stream of oil passing through lines 37 and 17. In order to secure thorough intermixture of solvent, oil and recycled raffinate, the mixture is passed by action of pump 22 from the feed end of chamber 15 via line 20 controlled by valve 21 into heater 23 wherein its temperature is raised, preferably to a point at which complete miscibility will occur. The mixture is then recycled via line 24 into the return end of mixing chamber 15. This circulation is preferably at a rate exceeding the rate of feed of all the streams entering the feed end of said mixing chamber so that there will be no flow of unmixed material from the feed end into the return end of the mixing chamber via the port 25 in division plate 26. The stream of oil, solvent and recirculated raffinate then passes via line 27 through cooler 28 and line 29 into settler 30. The mixture is cooled sufficiently in 28 to cause the desired phase separation in 30. Raffinate phase is removed from the settling chamber via line 33 controlled by valve 32. Extract phase exits through line 35 controlled by valve 36. In order to increase the proportion of raffinate to incoming oil for the purpose of accelerating phase separation in 30 by increasing the rate of coalescence of the raffinate phase therein, a portion of the raffinate accumulated in settling chamber 30 is intermixed with incoming fresh oil by passage through line 37 controlled by valve 38 by action of pump 39. Line 37 connects with feed line 16.

Due to the general similarity of the various hydrocarbon components of mineral oil fractions, such as lubricating oils, solubilities of the undesirable, non-paraffinic fractions and of the desirable paraffinic fractions in a selective solvent usually differ only in degree and there is, therefore, a tendency for desirable, high grade paraffinic oil to be carried away with the extract resulting in a loss in the yield of paraffinic fractions obtained. In other words, in a phase separation of extract and raffinate fractions from mineral oil employing a selective solvent, an equilibrium of paraffinic components as well as non-paraffinic components is established between the phases. Consequently, some of the desirable paraffinic fraction is found in the extract instead of in the raffinate.

For these reasons, the extract phase issuing from extraction chamber 30 via line 35 may contain a substantial proportion of valuable paraffinic fractions. The extract phase from settler 30 passing through line 35 is introduced into the feed end of mixing chamber 40 via line 34. Similar to mixing chamber 15, chamber 40 is also provided with division plate 26 and port 25 to separate the feed zone from the return zone. The extract phase is mixed in 40 with rejected oil, to be described, and the mixture passes from chamber 40 via line 41 through cooler 42 and line 43 into rejection chamber 45. The temperature of the mixture is sufficiently reduced in cooler 42 to cause separation of an insoluble rejected oil in chamber 45. A sufficient portion of said rejected oil may be recirculated into ad-

mixture with fresh quantities of the extract phase from extraction chamber 30 containing further quantities of reject oil to facilitate phase separation and coalescence of this insoluble oil 5 in settling chamber 45. This recirculated rejected oil passes into mixing chamber 40 by action of pump 48 via line 46 controlled by valve 47. In order to secure thorough intermixture of extract phase and recirculated rejected oil prior 10 to entrance into chamber 45, these materials may be passed from the feed end of mixing chamber 40 via line 50 controlled by valve 51 by action of pump 52, through heater 53 and into the return end of section 40 via line 54. By 15 recirculating through line 50, heater 53 and line 54 at a rate exceeding the rate of feed of all the streams entering the feed end of said mixing chamber, there will be no flow of unmixed material from the feed end into the return end of the 20 mixing chamber.

Extract phase is removed from rejection settler 45 via line 55 controlled by valve 56. The unrecirculated rejected oil produced therein can be removed from the system as an intermediate 25 raffinate or it may be returned through line 57 controlled by valve 58 by pump 59 into intermixture with that portion of the raffinate from extraction stage 30 which is recirculated into contact with fresh oil introduced into the system 30 in the above described manner.

In operation of this apparatus, a suitable proportion of recirculated raffinate from extraction stage 30 to solvent and oil entering the system may be one volume of recirculated raffinate to 35 two volumes of the mixture of solvent and fresh oil. In this case the volume of the final raffinate will be about one-third that of the oil fed into the system. This proportion, however, is not critical and may be varied from a small proportion 40 of recirculated oil which may be sufficient in certain instances up to a sufficiently larger proportion of recirculated oil and is limited only by the increased cost of pumping, heating and cooling the larger volumes of oil. Similarly, a 45 suitable proportion of rejected oil for recirculation from rejection stage 45 into contact with extract phase in mixer 40 is one volume of recirculated rejected oil to two volumes of extract phase. Preferably the draw-off lines for raffinate 50 and rejected oil to be recirculated are at lower points in the settling chambers 30 and 45 than the draw-off lines 33 and 57 in order to allow additional settling with consequent reduction in entrainment of extract phases in the withdrawn 55 oils.

In starting operations, there is, of course, initially no raffinate in the rejection stage and difficulty may be encountered in obtaining a raffinate to be recirculated therein as the tendency for coalescence without sufficient recirculation is low. For this reason, connection 60 controlled by valve 61 has been provided to introduce oil feed directly into the rejection stage in order to build up a raffinate in this stage so that 60 recirculation of raffinate may be initiated therein.

Many variations and modifications of the above described invention will be obvious to a man skilled in the art. For instance, additional stages of extraction may be provided; mixing 70 chambers 15 and 40 may be omitted whereby the mixing will occur directly in heaters 23 and 53, respectively, and similar changes may be made. It is understood that the foregoing is merely illustrative of the generic invention set forth in 75 the following claims.

I claim:

1. A process for the separation of paraffinic and non-paraffinic fractions from mineral oil containing the same which comprises extracting said oil with a selective solvent to produce a 5 raffinate insoluble in said solvent and an extract phase, separating said raffinate from said extract phase, heating a portion of said raffinate with further quantities of selective solvent and said oil to complete miscibility prior to extraction, extracting the mixture at a lower temperature, and thereby forming a raffinate phase and an extract phase and separating said phases. 10

2. A process for the separation of paraffinic and non-paraffinic fractions from mineral oil containing the same which comprises extracting said oil with a selective solvent to produce a 15 raffinate insoluble therein and an extract phase in an extraction stage, cooling said extract phase to produce an insoluble rejected oil and intermingling further quantities of oil entering the said extraction stage with said rejected oil and with a portion of the raffinate from said extraction stage prior to extraction therein. 20

3. A process for the separation of a hydrocarbon oil mixture into fractions relatively more paraffinic and fractions relatively less paraffinic in character than the original hydrocarbon oil mixture which comprises admixing said hydrocarbon mixture with oil which is relatively more 25 paraffinic in character than said hydrocarbon oil mixture and further characterized by containing a substantial proportion of oil fractions having the same boiling range as the oil fractions 30 contained in the hydrocarbon oil mixture and thereby increasing the ratio of paraffinic fractions to non-paraffinic fractions in said mixture, commingling the hydrocarbon oil mixture which has been admixed with said relatively more 35 paraffinic oil with a selective solvent and thereby forming an extract phase and a raffinate phase 40 and separating said phases. 45

4. A process as claimed in claim 3 in which the oil admixed with the hydrocarbon mixture is an 45 oil which has previously been extracted with a selective solvent.

5. A process for the separation of a hydrocarbon mixture into fractions relatively more paraffinic in character and fractions relatively less paraffinic in character than the original oil which comprises admixing said hydrocarbon mixture with a selective solvent and with oil which is relatively more paraffinic in character than said hydrocarbon oil mixture and further characterized by containing a substantial proportion of oil fractions having the same boiling point range as the oil fractions contained in the hydrocarbon mixture, heating said mixture of oil and selective solvent to a temperature sufficiently high to cause substantial complete miscibility between the oil and the solvent, passing the solution of oil and solvent through a cooler and cooling the solution sufficiently to cause phase separation between the relatively more paraffinic oil fractions and the relatively less paraffinic oil fractions dissolved in the selective solvent. 55 60 65

6. A process according to claim 5 in which the oil admixed with the hydrocarbon mixture is an oil which has previously been extracted with a selective solvent. 70
